UNION UNDERGARMENT.

1,105,701.

Specification of Letters Patent. Patented Aug. 4, 1914.

Application filed November 8, 1911. Serial No. 456,778

To all whom it may concern:

Be it known that I, Michael F. Rodischon, of Utica, in the county of Oneida and State of New York have invented certain new and useful Improvements in Union Undergarments; and I do hereby declare that the following is a full, clear, and exact description thereof, which will enable others skilled in the art to which it appertains to make and use the same, reference being had to the accompanying drawings, and to the reference-numerals marked thereon, which form part of this specification.

The purpose of my present invention is to provide an improved union undergarment having certain features of construction that make it easier to get into or out of than heretofore; and that render the garment more comfortable, convenient and healthful in use. The garment is simple in construction and operation and requires only two buttons or fastening members thereby resulting in economy in manufacture and greater ease and quickness in dressing or undressing. Furthermore the construction is such that these two buttons are so placed as to avoid their being pressed against the body by other clothing.

My invention relates only to that class of union undergarment that is entered from the top by enlarging the neck opening.

Figure 1 is a front view of a union undergarment embodying my invention. Fig. 2 is a diagrammatic cross sectional view taken 35 through the garment on line 2—2—2—2 of Fig. 1 and showing the overlapping arrangement of the placket pieces. Fig. 3 is a sectional view on an enlarged scale through the front placket on line 3—3 of Fig. 1. Fig. 4 is a sectional view on an enlarged scale 40 through the back placket on line 4—4 of Fig. 1. Fig. 5 is a plan of one of the placket pieces. Fig. 6 is a front view of the upper part of the garment with both plackets 45 opened.

It will be understood that in all the sectional views the thickness of the material is exaggerated.

The union garment is made of the usual 50 elastic knitted or netted material, tubular in form so as to form the general body portion 8 without seams, while the leg portion 9 is formed in the usual way by cutting out wedge shaped sections and sewing up the inside edges. The upper end of the tube is

brought together to form the shoulders 10 leaving therebetween a circular neck opening 11. From the neck opening in both front and back the material is cut some distance down through the body of the garment, leaving two edges 12 and 13 on the right and left in front and 14 and 15 on the right and left in the back. To the front edge 12 the edge 16 of a placket piece 17 of similar material is sewed. This piece is of the shape shown particularly in Fig. 5 being a triangle with the sharp point cut off. The wide end 18 of the placket piece is sewed to the inside of the body to the right of the edge 12, while the slanting side 19 preferably having an edging 20 extends upwardly in a slanting direction to the neck 11 where the short end 21 lies under the upper corner of the edge 12 which has a button hole 22 to receive a button 22a upon the under portion. A facing strip 23 is sewed to the edge 12 and finishes off the front of the garment and covers up the seam at the junction of edge 13 and the edge 16 of the placket piece. A binding strip 24 may be secured over the inner side of this seam to keep the rib down flat and cover the same. At the back a similarly shaped and arranged placket piece 17 is secured to the edge 15, projects across beneath the other side edge 14 and is secured to the body of the garment. A similarly arranged button 25 near edge 15 and button hole 26 near the edge 14 hold the garment together in the back. A binding 27 is sewed over the edge 14 and a binding strip 28 over the inwardly projecting rib of the seam formed by the union of the edge 15 and the edge 16 of the back placket piece.

It will now be evident that I have constructed a union undergarment that is entered or left from above very easily by reason of the two openings adjacent to the neck opening itself that when opened form one very wide opening. This one large opening so formed is sufficiently large to allow the person to get into or out of the same from above very easily, without unusual movement of the body, and without straining or stretching the garment. Moreover by reason of this opening extending down from the neck both in front and behind, the garment can be drawn on without the usual twisting of the same and the arms can be thrust into or withdrawn from the arms 29 of the garment much easier than

where the extra opening is all on one side or at the front or at the back of the neck opening. A further advantage of my invention is that by using the two relatively short slits at front and back each of these slits can be closed by only one button situated at the top near the neck. This gets a minimum of fastening members. Moreover it locates such as are needed where they will not give discomfort to the wearer in that they are near the neck where they will not be pressed against the body as one leans against a chair and where there are no tight garments to press them against the body. This latter point is of great importance to ladies in that it particularly avoids the presence of any buttons between the corset and the body. It further avoids any buttons at the sides of the neck or over the shoulders or over the chest where they are uncomfortable to man or woman.

By means of my construction the two short openings can be guarded from spreading open by means of the underlapping placket pieces with their relatively wide bases which keep the placket pieces in place while they do not extend far enough down or to the side to be bulky or uncomfortable as would be the case were one opening twice as long used with a proportionately broad-based placket piece.

By the term union under-garment as used herein I mean to include not simply such garments as are used as undergarments in the strict sense of being worn under a person's dress clothes but also sleeping garments entered, made like and having the advantages of the construction above set forth.

Such garments are worn especially by children and have the special advantage of eliminating the row of buttons down the front or back that have heretofore been used.

What I claim as new and desire to secure by Letters Patent is:

1. A union undergarment of the class entered by means of enlarging the neck opening, having the main body portion formed from one piece of tubular material and slit downwardly from the neck at the front and at the back, about half way to the waist line, triangular placket pieces secured to one edge of each slit and extending beyond the opposite edge of the body and secured thereto at its base and fastening members for holding closed the neck ends of the slitted body.

2. A union undergarment of the class entered by means of an opening at the neck end, having a main body portion formed from one piece of tubular material with a neck opening downwardly from said neck to about half way to the waist line a slit in front and a slit in the back and triangular placket pieces secured to one edge of each slit and extending beyond the opposite edge of the body and secured thereto at its base and fastening members for holding closed the neck ends of the slitted body.

In witness whereof I have affixed my signature, in the presence of two witnesses, this 27th day of October, 1911.

MICHAEL F. ROBISCHON.
